[57] **CLAIM**

The ornamental design for a flash light, as shown and described.

DESCRIPTION

FIG. 1 is a perspective view showing the top, front and one side of a flash light showing my new design;

FIG. 2 is a perspective view of the bottom, rear end and opposite side thereof;

FIG. 3 is a top plan view thereof;

FIG. 4 is a front end elevational view thereof; and,

FIG. 5 is a top, front and one side perspective view of another embodiment thereof, the only difference being in proportion.

FIG. 1

FIG. 2

FIG. 3

FIG. 4

FIG. 5
